UNITED STATES PATENT OFFICE

EDWARD J. SOVATKIN, OF BROOKLYN, NEW YORK, ASSIGNOR TO J. SKLAR MANUFACTURING CO., INC., OF BROOKLYN, NEW YORK, A CORPORATION OF NEW YORK

CUTLERY

Application filed December 26, 1929. Serial No. 416,438.

This invention relates to cutlery. It is directed to a surgical clamp and the like instruments.

An object of the invention is to provide in an instrument of the character described, having a mortise joint between the crossing portions of the instrument, means for adjusting the device to tighten or loosen the connection between said crossed portions, whereby true alignment between the jaws or working points of the instrument may be effectively maintained, the construction nevertheless being such as to provide for smooth and efficient operation and great durability.

15 A further object of this invention is to provide a neat, compact, rugged instrument of the character described, which shall be comparatively inexpensive to manufacture, comprise few and simple parts, easy to assemble and manipulate and which shall yet be smooth in operation and practical and efficient to a high degree.

Other objects of this invention will in part be obvious and in part hereinafter pointed out.

The invention accordingly consists in the features of construction, combinations of elements, and arrangement of parts which will be exemplified in the construction hereinabove described, and of which the scope of application will be indicated in the following claims.

In the accompanying drawings, in which is shown one of the various possible illustrative embodiments of this invention,

Fig. 1 is a top plan view of an instrument embodying the invention;

Fig. 2 is a fragmentary perspective view of the instrument with the jaws open;

40 Fig. 3 is a cross-sectional view taken on line 3—3 of Fig. 2; and

Fig. 4 is a cross-sectional view taken on line 4—4 of Fig. 3.

Referring now in detail to the drawings, 45 10 designates an instrument embodying the invention in the form of a surgical clamp or forceps comprising a pair of crossed members 11 and 12 pivoted to one another, in the manner hereinafter appearing, as at 13.

50 Said members 11 and 12 comprise arms 11a

and 12a and jaws 11b and 12b respectively. Looped handle portions 14 and 15 extend from the rear ends of the arms 11a and 12a respectively, for receiving the user's fingers. Preferably integrally formed with the arm 11a is a ratchet member 14b adapted to cooperate with a pawl 15b extending from the arm 12a, for releasably retaining the arms in clamped position.

The jaws 11b and 12b may be curved and formed with serrations 16 and 17 on the inner faces thereof respectively. The jaw 12b may further be provided with a "mouse tooth" 18 at the end thereof adapted to cooperate with a complementary groove or recess 19 formed on the outer end of jaw 11b.

In instruments having crossed, interpivoted portions, generally, and particularly in the type of forceps or clamp having a "mouse tooth" construction, it is of great importance to maintain the jaws in substantially perfect alignment. To this end, in accordance with this invention, member 11 is formed with a central slot 25 forming spaced, thin, parallel guide plates for portions 25a and 25b for snugly receiving therebetween a reduced portion 26 formed on the member 12 and thus providing a mortise or box joint or lock ensuring alignment between the jaws. It will be noted that member 12 is provided with substantially parallel shoulders 27 defining the ends of the reduced portion 26 adapted to engage shoulders 28 formed on member 11 upon closing the instrument.

Difficulty has been found, however, in the use of the box or mortise joint or lock in instruments of the type generally shown herein, and provided with an ordinary rivet for pivoting the crossed portions, since with continual sterilization the locks may become rusted on the inside thereby causing the instrument to stick or become too tight to prevent the proper operation of the same. Furthermore, with continual use, wear often causes the lock to become too loose. For obviating these difficulties, means is provided for adjusting the joint to permit tightening or loosening of the same. To this end, the reduced portion 26 is provided with a bore or opening 29. Said guide portion 25a is

provided with an opening 30 aligned with said opening 29 and with an enlarged opening 31 concentric with said openings 30 for the purpose hereinafter appearing. The 5 guide plate or portion 25b is provided with a screw threaded opening 32 aligned with the openings 29 and 30. A screw 35 having a head 36 and screw threaded end portion 37 provides the pivot for the members 11 and 10 12. The head 36 engages within the enlarged opening 31 and abuts the shoulder 38 formed by said opening. The screw threaded portion 37 engages the screw threads of opening 32. It will be noted that the opening 29 is 15 somewhat larger than the shank of the screw so as to prevent engagement between the screw and said portion 26.

The connection between members 11 and 20 12 may be tightened by turning the screw in one direction to draw the guide plate portions 25a and 25b, which are relatively thin and hence somewhat flexible, toward one another and pressing the same into tight frictional engagement with the opposite faces 25 of portion 26. For loosening the connection between said members 11 and 12, the screw need merely be turned in the opposite direction to relieve pressure and frictional engagement between portions 25a and 25b with 30 the interposed portion 26. The user may thus easily and quickly adjust the instrument when desired, the screw head 36 being provided with a kerf 40 for receiving a screw driver for this purpose.

35 Although scissors, clamps and the like have been made with screw joints, difficulty has been experienced with such constructions, since when the screws become loose, the jaws easily get out of alignment. A dominant 40 feature of this invention is the incorporation into a single instrument such as a surgical clamp or forceps, of a mortise or box lock and an efficient adjusting means whereby alignment of the jaws is insured and adjustment of the instrument is nevertheless provided for, thus providing a highly efficient, 45 practical and durable instrument.

It will thus be seen that there is provided 50 a device in which the several objects of this invention are achieved, and which is well adapted to meet the conditions of practical use.

As various possible embodiments might be 55 made of the above invention, and as various changes might be made in the embodiment set forth, it is to be understood that all matter herein set forth or shown in the accompanying drawings is to be interpreted as illustrative and not in a limiting sense.

60 Having thus described my invention, I claim as new and desire to secure by Letters Patent:

1. A surgical clamp comprising a pair of 65 crossed members having curved jaws, a tooth c3 at the end of one jaw, the other jaw being

formed with a recess for receiving said tooth, a mortise joint for said member, and a screw pivotally interconnecting said members at said joint adapted to adjust the degree of frictional engagement between said members. 70

2. A surgical clamp comprising a member having a thru slot forming a pair of spaced parallel portions, a second member having a portion extending thru said slot and between said parallel portions, jaws curved out of the plane of said members extending therefrom, one of said jaws being formed with a tooth at the end thereof, the other jaw being formed with a recess for receiving said tooth, and a screw pivotally interconnecting said members, said screw having a head contacting one of said parallel portions and a portion having screw threaded engagement with said other parallel portion only. 75

80 3. A surgical clamp comprising a member having a thru slot forming a pair of spaced parallel portions, a second member having a portion extending thru said slot and between parallel portions and a screw pivotally interconnecting said members, one of said portions having a recess on the outer side thereof, said screw having a head received within said recess and a shank portion having screw threaded connection with the other of said parallel portions. 85

90 In testimony whereof I affix my signature.
EDWARD J. SOVATKIN.
